UNITED STATES PATENT OFFICE.

WARREN M. BRINKERHOFF, OF AUBURN, NEW YORK.

DESIGN FOR A BOOK-COVER.

SPECIFICATION forming part of Design No. 26,964, dated April 27, 1897.

Application filed March 15, 1897. Serial No. 627,698. Term of patent 14 years.

To all whom it may concern:

Be it known that I, WARREN M. BRINKERHOFF, a citizen of the United States, residing at Auburn, in the county of Cayuga and State of New York, have invented and produced a new and original Design for a Book or Catalogue Cover; and I do hereby declare the following to be a full, clear, and exact description of the same, reference being had to the accompanying drawing, forming a part thereof.

My design is illustrated in the accompanying drawing, which shows a face view of a book-cover ornamented by my invention.

In the said drawing, A A A designate figures of mower-knife sections, of which there

are three rows with five figures in each row. Within the marginal lines of each figure is placed a smaller figure of a knife-section of like character which is designated by the reference-letter *a*.

What I claim, and desire to secure by Letters Patent, is—

The design for a book-cover substantially as herein shown and described.

In testimony whereof I have affixed my signature in presence of two witnesses.

WARREN M. BRINKERHOFF.
